UNITED STATES PATENT OFFICE

SAMUEL EDWARD SETTLEMOIRE, OF EVANSVILLE, INDIANA

CURTAIN ROD

Application filed February 15, 1929. Serial No. 340,084.

The object of this invention is to provide a simple, inexpensive, neat and unobtrusive adjustable curtain rod which can be quickly and easily applied to any window frame 5 without requiring the use of nails, screws, fastenings of any kind, or tools and without disturbing the window shade.

My invention comprises two rods of stout and yet suitably resilient metal having an adjustable connection, such as a tube in which they are entered, and provided with improved ears and penetrating points, the ears being adapted to lie against the window frame after the points have been pressed into the edges of said frame. Thus, the curtain rod may be applied to a window frame of any width and will remain in position, without requiring the use of fastenings or tools, and can be readily taken down when desired.

20 In the accompanying drawings:

Figure 1, is an elevation of a window and its frame, showing my curtain rod in position;

Fig. 2, is a plan view thereof; and

25 Fig. 3, is a plan view of the rod, the sleeve or tube being in section.

The window frame appears at 1 and an ordinary window shade is shown at 2.

My improved curtain rod is shown, generally, at 3.

The curtain rod comprises complementary sections 4, 5 of stout wire or rod, the horizontal parts of these sections being adjustably received within a sleeve or tube 6 which affords means whereby the sections may be moved away from each other so that the rod may be connected to a window frame of any width.

The sections have a bent part 7 adapted to be disposed horizontally when the rod is in position on the window frame, and loops constituting vertically arranged ears 8 which are adapted to lie against the front of the window frame to prevent the rod from tilting downwardly, and said sections 4 and 5 terminate in curved or arched parts 9 and penetrating points 10, said parts 9 and 10 being arranged horizontally when the rod is in position.

50 The prongs or points 10 are intended to enter the edges of the frame 1.

Having placed the curtain on the rod, the latter may be secured to the frame merely by positioning the rod at the proper height and exerting sufficient pressure on the ends of the rod sections to cause the prongs 10 to penetrate the side edges of the frame 1. The ears 8 then lie vertically, as shown in Fig. 1, and by engaging the front of the window frame, prevent the rod from falling. The ears are, however, concealed by the curtain and do not detract from the neat appearance of the rod.

55 What I claim is:

A curtain rod comprising complementary sections adjustably connected together so that the sections may be contracted or expanded in relation to each other, each of said sections having a straight, curtain-suspending part and formed at its outer end into a single incomplete loop constituting an ear arranged to lie flat against the front of the 70 window frame when the rod is in position on a window frame, and terminating in a laterally disposed hook located wholly rearwardly of said loop and provided with a penetrating point adapted to enter the side edge of 75 the window frame, the hook lying in a plane which is substantially at right angles to the plane of the loop.

80 In testimony whereof I affix my signature.

SAMUEL EDWARD SETTLEMOIRE.
